Primary Examiner — Eliza Z Bennett-Hattan(74) *Attorney, Agent, or Firm* — Norton Rose Fulbright
US LLP(57) **CLAIM**

The ornamental design for an power driven surgical tool, as shown and described.

DESCRIPTION

FIG. 1 is a perspective view of the power driven surgical tool;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines disclose unclaimed environmental structure while the dash dot lines represent the boundary of the claim and form no part of the claimed design.
